Primary Examiner — Ian Simmons*Assistant Examiner* — Carissa C Fitts(74) *Attorney, Agent, or Firm* — Husch Blackwell LLP**CLAIM**

The ornamental design for a safety light, as shown and described.

DESCRIPTION

FIG. 1 is a front perspective view of a safety light in accordance with an embodiment of the present invention.

FIG. 2 is a top view thereof;

FIG. 3 is a bottom view thereof;

FIG. 4 is a front view thereof;

FIG. 5 is a right side view thereof;

FIG. 6 is a rear view thereof; and,

FIG. 7 is a left side view thereof.

The broken lines shown in all figures represent unclaimed portions of the safety light and form no part of the claimed design.
